UNITED STATES PATENT OFFICE

ADOLF ROHRBACH, OF BERLIN-WILMERSDORF, GERMANY

FLOAT CONSTRUCTION FOR HYDROPLANES

Application filed February 27, 1929, Serial No. 343,124, and in Germany February 27, 1928.

This invention relates to a boat or float structure, intended principally for use as hull construction for hydroplanes, and for floats that are used for supporting flying boats 5 while resting upon or rising from the water. The design embodying the invention provides an upper body or hull portion above the submersible bottom which upper hull has flaring or diverging side walls 10 so that at its narrowest portion it is wider than the widest portion of the submersible lower body or bottom. This bottom body is intended to facilitate the gliding action upon the surface of the water of a hydroplane or other form of boat; and also for enabling a flying boat to take-off from the water with greater ease and less resistance to its motion upon or through the water in the act of taking off. The invention may be 15 used to advantage with a boat or float having its bottom surface arranged in step formation, or the invention may be used in connection with boats or floats not so constructed.

When used with a float having its bottom 20 surface arranged in stepped formation, the invention is useful and of advantage providing increased space in the upper portion of the hull in combination with a submersible hull portion or bottom which is useful in reducing the tendency of the water-waves to 25 cling to the sides and bottom of the hull, which clinging action produces friction and increases the resistance to movement of the hull through or upon the water.

In previously designed hulls or float structures while the bottom portions have been 30 designed to facilitate the taking off and alighting of the machine, the upper hull structure associated therewith has comprised 35 side walls which arise substantially vertically to the deck. I have re-designed the upper portion of the hull so that while advantage 40 may still be taken of the improved function of the submersible bottom the upper body has 45 been enlarged so as to provide additional

room or cargo space without necessitating a proportional increase of width of the bottom. As a result, the weight of the bottom, has not been increased since by the present invention substantially the same bottom girders are employed as in the prior structure, the necessary strength being obtained without waste of constructive material or increased weight.

A further advantage results in the use of 50 the invention in transport planes, the gain of space toward the ceiling or top deck resulting in increased comfort to the passengers. Moreover, the enlargement of the upper hull structure or body cabin accommodates larger 55 quantities of luggage or freight and affords additional room for parts such as bilge piping and control pulleys; while also enlarging the field of view of the persons carried. In the case of war planes this divergence of 60 the upper walls increases the firing range. Furthermore the overhanging side walls intercept lateral waves so as to prevent or minimize the influx of spray.

In the respects noted the present invention 65 is an improvement on the invention disclosed in my copending application, Serial No. 184,751 filed April 18, 1927.

My invention is illustrated in the accompanying drawings which form a part of this 70 specification. In the drawings,

Fig. 1 is a front elevation of a flying boat the hull of which and also the supporting floats are constructed in accordance with this 75 invention.

Fig. 2 is a side elevation of the same boat.

Fig. 3 is a side elevation partly in section.

Fig. 4 is a transverse section on the line II—II of Fig. 3.

Fig. 5 is a front elevation of the bow of a 80 boat or float illustrating the development of the forward gliding surfaces.

Figs. 6 and 7 are respectively side and bottom views of the construction shown in Fig. 5.

Referring to Figs. 1 and 2, the hull struc-

ture of the boat is indicated by reference numeral 16, and the floats by numeral 17. In these views the hull of both the boat and float structures is shown as having upwardly and outwardly flaring sides, the width of the bottom of the hull in contact with the water being somewhat less than the greatest cross-section width of the boat. As indicated, three motors 2 may be employed, arranged above the monoplane wings 1 and braced against the latter by struts 3. Truss members 4 serve as connections for the inclined struts thus supplementing the latter. The high-deck wings 1 comprise longitudinal beams 9, 10, which are connected by spaced cross ties 8, a suitable covering or skin being provided. Suitable connections between the floats 17 and the wing 1 and also the hull 16 are indicated at 18 and 19.

20 In Fig. 2, the angle of incidence made by the surface of the bottom of the hull structure is illustrated.

Referring to the Figures 3-7 inclusive, comprising Sheet 2 of the drawings, it will be found that I provide a sharp keel *b'* which at the forward end of the ship or float may be continued to form a prow structure.

At the forward end *a'* of the bottom *n* of the boat *a*, and extending forwardly of the first step *m*, I provide on each side of the keel *b'* one or more concave surfaces *e* which may be designated as gliding surfaces. In Figs. 3 and 4 one such a concave surface or groove *e* is provided at each side of the keel, and the effect upon the bottom surface of the hull with this construction is well illustrated in the sectional view of Fig. 4. The depth of the concavity preferably diminishes somewhat toward the forward end of the ship and the gliding surfaces are combined with the remainder of the forward bottom part of the ship or float in a proper manner to give to the bottom surface the proper desirable angle of incidence.

45 It is to be noted that the gliding surfaces *e* meet the upwardly and outwardly flaring sidewalls of the hull at a somewhat acute angle, shown at *c'*; the effect of which, as in taking off, is to direct the water downwardly and prevent, in an appreciable measure, the tendency of the water to rise and cling to the sides *a'* of the hull. This same result and effect is augmented and increased by adding to the number of gliding surfaces or grooves 50 to either side of the keel, and an effective arrangement of this kind is illustrated in Figs. 5-7, in which the additional and symmetrically arranged surfaces are illustrated at *t*. By this construction additional edges *t'* are provided, which, in a similar way to that described in connection with the edge *c'*, counteract the clinging tendency of the water and waves to the sides of the hull.

The further advantage in this construction 65 is that it affords a hull which is wider in aver-

age beam and deck than is the bottom. A substantially lighter hull structure is provided by my invention in which only light weight stiffening girders are required in the bottom *n*. The hull structure, above the water line with its outwardly flaring sides provides enlarged space within the hull for the more adequate and comfortable accommodation of passengers on seats *o* and cargoes. Nets *p* are provided above the seats *o*. In the roof there are channels for control cables *s* leading from the pilot's seat to the ailerons *r* and the tail planes *q*; and also for bilge pipes *u* or the like. From the sight lines *v*, shown in broken lines in Fig. 4, it appears that particularly in the downward direction there are wide fields of vision meeting below the bottom *w* in an extension of the bottom part disposed in front of the step *m*. The side floats *i* shown in Fig. 4 are constructed in accordance with the principles of the invention.

With ships or floats having stepped bottoms, the modified bottom surface with gliding surfaces need not extend rearwardly of the first step, but I do not desire that this invention be understood as limited to a stepped hull construction, since it will be clear that it can be used to advantage with other known types of hulls, and with all of the advantages herein set forth. Obvious changes to details of construction illustrated may be made and will be suggested to one skilled in the art without departing from the scope of my invention.

What I claim and desire to protect by Letters Patent is:

1. A floating body for hydroplanes having a stepped bottom laterally curved forward of the step between the keel and chines to provide concaved sides whose vertices are higher than the chines, the side walls of the upper body portion above the chines flaring outward and upward so that said upper body portion at its narrowest is wider than the submersible part of the floating body at its widest.

2. A floating body for hydroplanes having a stepped bottom laterally curved forward of the step between the keel and chines to provide concaved sides whose vertices are higher than the chines, the bottom being provided at a substantial distance aft of the bow with relatively short and narrow gliding surfaces adjacent to the keel and terminating at the step, the side walls of the upper body portion above the chines flaring outward and upward so that said upper body portion at its narrowest is wider than the submersible part of the floating body at its widest.

3. A hydroplane comprising a main body structure and two separate float structures spaced laterally from the body structure, the body structure having a stepped bottom laterally curved forward of the step between the keel and the chines to provide concave sides,

the side walls of the upper portion of the body structure above the chines flaring outward and upward so that the upper body portion of the body structure at its narrowest is
5 wider than the submersible part at its widest, the two lateral float structures each having a bottom of pronounced V-shape with the walls above the bottom diverging upward and outward.

10 In testimony whereof, I have signed my name to this specification.

ADOLF ROHRBACH.
